GAS DISPENSER

Jay A. Heidbrink, Walter E. Michaelson, and Wayne W. Hay, Minneapolis, Minn., assignors to Air Reduction Company, Incorporated, New York, N. Y., a corporation of New York

Application June 12, 1944, Serial No. 539,956

3 Claims. (Cl. 222—3)

1

Our invention relates to valve mechanism which is particularly adapted for use in connection with small containers of oxygen, initially at very high pressure, adapted to be carried in a pocket of the uniform of an aviator in conjunction with a parachute escape device including a mouth mask, so when forced to bail out at high elevation he will have a supply of oxygen to last him until he gets into air with a sufficient oxygen content for safe breathing.

Inasmuch as such tanks necessarily must be small and a sufficient quantity of oxygen must be supplied for keeping an aviator alive for descents from up to five miles and more, the oxygen has to be stored at a very high initial pressure. The conditions of storage must be absolutely leak-proof, since these tanks may be carried for many weeks or months without use, and it is not practical to test them otherwise than from an inspection of the gauge to show the pressure of the gas within the tanks. For this reason the valve mechanism must be permanently attached to each of these tanks and so sealed in that leakage is impossible. This presents a problem in the filling and refilling of such tanks which has involved very great difficulties.

Heretofore the filling of these tanks has been effected by way of the same opening which carries the gas to the breathing passages. Such an arrangement prevents proper screening of the gas, also where, as here, a limit port of minute cross-section is employed, very great difficulties have been encountered in preventing particles of dust or casing flake from entering the limit port and blocking flow of gas therethrough.

Also there is another problem in the valve structure of an apparatus for use in connection with parachute escape devices, which is that the valve for delivering the oxygen to the aviator must open instantly to full delivery capacity, and readily open in that manner with a single free movement of one hand of the aviator.

It is a principal object of our invention, therefore, to provide valve mechanism which may be sealed into a small tank or bottle capable of withstanding high pressures of gas delivered thereto up to an initial pressure of 2500 pounds and a final pressure of around 1800 pounds per square inch, and to provide means for filling a tank with gas at such high pressure wherein the filling passages are entirely distinct and separate from the passages for delivery to the breathing line, and wherein the valve means for admitting the gas for filling or refilling the tank is self-opening upon being subjected to the pressures

2

from the filling tank and self-closing when that pressure is turned off.

It is a further object of our invention to provide passageways from the interior of the tank leading to a valve chamber wherein is a limit port of quite considerable length and which is formed in a material of substantially negligible coefficient of expansion, as for example glass, through which the high pressure gas must pass to reach the breathing line.

It is a further object of our invention to arrange the elongated limit port transversely of the valve mechanism for delivering the gas to the limit port so that the height of the entire valve member may be reduced to a minimum, and also for use and convenience in inserting and withdrawing it without the necessity of taking off or disturbing other parts of the assembly.

It is a further object of our invention to provide a plunger operated by a single swinging lever, said plunger having a needle valve at one end and a disc valve above the needle valve, so positioned relative to a circular valve seat in the casing that when the valve handle is swung up the needle valve will be thrown to fully open position and the disc valve will simultaneously be brought to engage the valve seat to shut off possibility of escape of waste gas from the valve chamber.

The full objects and advantages of our invention will appear in the description given in the appended specification and the novel features by means of which the aforementioned advantageous results are obtained will be particularly pointed out in the claims.

35 In the drawings illustrating an application of my invention in one of its forms:

Fig. 1 is a front elevation view of the exterior of the valve mechanism as attached to the gas container.

40 Fig. 2 is a sectional elevation view taken on line 2—2 of Fig. 1 viewed in the direction of the arrows.

Fig. 3 is a plan view partly in section of the mouth mask, adapted to be quickly inserted in the aviator's mouth which is connected with the valve casing for delivery of oxygen to the aviator.

Fig. 4 is a sectional plan view taken on line 4—4 of Fig. 2.

Fig. 5 is a sectional plan view taken on line 5—5 of Fig. 2.

Fig. 6 is a sectional plan view taken on line 6—6 of Fig. 2.

Fig. 7 is a plan view of a gauge front used in connection with the valve.

55 Fig. 8 is a side elevation view showing the yoke

means for holding the connector member in position for filling the small tank from a large supply tank.

Referring to the drawings and particularly Fig. 2 thereof, a main valve casting 10 is provided with three internally-threaded openings 11, 12, and 13. Around the opening 11 at 14 is a semi-conical accurately milled bearing 14. An externally-threaded shank 15 of a closure head 16 is screwed into the internal threads of the opening 11 until a conical shoulder 17 on the head 16, which is milled smooth and true to fit the seat 14, also milled smooth and true about the opening 11, contacts said seat resulting in a complete metal to metal seal of the opening.

The opening 11 has at its bottom a screen 18 which is held in position by a lock ring 19. The screen 18 overlies an opening 20 which connects with the chamber 12 and which is surrounded at its entrance to chamber 12 by a knife-edged valve seat 21. Within chamber 12 is a valve block 22 which is provided with a series of channels along its sides opening to the internally-threaded portion of the chamber 12.

A cap screw 24 is provided with an externally threaded portion 25 which screws into the internal threads of the threaded portion of chamber 12. The cap screw also has thereon a semi-conical bearing face 26 which is adapted to engage a similar semi-conical face 27 at the edge of the threaded part of opening 12. The conical faces 26 and 27 are of similar dimension and are milled true and smooth so when the cap screw 24 is screwed down tight a complete metal to metal seal is effected between conical surface 26 and conical surface 27.

The valve block 22 is provided with a recess 28 and the cap screw 24 is provided with a recess 29 which fronts the recess 28. Within these two recesses is positioned a compression spring 30 which, when the cap screw 24 and head 16 are in sealing position, or when there is no pressure upon the valve piece 22, will hold the valve piece 22 upon the valve seat 21 and thus seal communication with the passageway 20.

The valve casting 10 is provided with a threaded nipple member 31 to which is threaded the neck end 32 of a small heavily-walled container 33 adapted to hold oxygen gas at high pressure. By welding, soldering or otherwise, as shown in Figs. 1 and 2 at 33', the nipple member 31 and container 33 are permanently joined and hermetically sealed. A port 34 extends through the nipple member 31 into the chamber 12. Gas from the chamber 35 within the gas container 33 may pass through that port to chamber 12 and through channels 23 to the space 36 between adjacent faces of valve block 22 and cap screw 24 and said gas will ultimately reach a port 37 leading to a passageway 38 which connects through a nipple 39 with a gauge 40, Fig. 2. The gauge 40 is provided with a dial 41 on which are calibrations 42 indicating gas pressures to 3,000 pounds per square inch. The calibration 1800 is associated with the word "full," Fig. 7. Hence, when the needle 43 points to 1800 or to any figure above 1800, the aviator is advised that he has a tank or container of oxygen of the full amount required, 1800 pounds per square inch being the preferred pressure for a full tank of oxygen.

It will be noted that this gauge and the oxygen pressure recorded by it have no connection with the passageways which deliver gas to the passageways leading to the breathing line of the aviator. Hence, the pressure indicated is always a correct

pressure based upon the actual contents of oxygen gas in chamber 35 of container or tank 33.

When for any reason the gas in tank 35 is either exhausted or reduced in quantity a fresh supply of gas may readily be introduced into and sealed in the gas container 33 in the following manner:

The cap screw 16 is withdrawn, leaving the chamber 11 entirely open with the conical bearing 14 surface 17 at its outer margin exposed. A connector member having a head 44, a shank 45, and a conical beveled face 46, will then be applied to the opening 11 with the conical face 46 engaging the conical face 14. The connector member is provided with a hook 48 of a yoke member 49, which straddles laterally the valve casting 10, Fig. 8. A hand wheel 50 has a conical point 51 which engages in a conical seat 52 in the center of cap screw 24. By screwing the hand wheel 50 upon the seat 52 the conical walls 46 of head member 44 will be drawn into metal to metal sealing engagement with the conical wall 14. The shank 45 of connector member is united at 45' through neck 46' with large supply tank of oxygen 47, the flow of oxygen therefrom being controlled by valve 47.

When the valve 47 from the storage tank, of usual construction, is opened, the pressure of the gas from the storage tank will push the valve piece 22 from the valve seat 21 against the pressure of spring 30, thus permitting gas to flow through opening 20, chamber 12, and passageway 34, into chamber 35 in the storage tank 33. At the same time this gas will flow about the valve piece 22 through passages 23, and passages 37 and 38 to the gauge 40.

Thus, as the tank is being filled with gas, the needle 43 will indicate on the calibration scale 42 the ultimate pressure of gas in the container 33. By watching that needle and adjusting the rate of flow of gas into container 33, the operator can determine the point at which the pressure within container 33 reaches 1800 pounds per square inch and at that point can shut off delivery of gas from the storage tank. Since then the pressure of gas in chamber 12 is uniform, about the valve block 22, the spring 30 will immediately restore said valve block into sealing engagement with the knife-edged valve seat 21. The connector head 44 can then be withdrawn and the cap screw 16 restored into sealing position, and thus the gas containing tank 33 be filled or refilled very simply and without any loss of gas.

Sealed in the nipple 31 is a tube 55 which extends directly into the chamber 35 of gas container 33. This tube has secured to its lower end a head piece 56, Fig. 2, formed with a chamber 57 therein. A set of screens 58 is held to cover the otherwise open bottom of the chamber 57 by means of a lock ring 59. From the inner end 60 of tube 55 a passageway 61, Fig. 6, also in dotted lines, Fig. 4, extends through the nipple 31 and valve block 10 into a chamber 62 which is positioned inwardly from the internally-threaded opening 13.

The chamber 62, Fig. 5, is formed with a smoothly milled conical bearing surface 63 and receives the head member 64 of a cylindrical member 65 which is seated in the opening or chamber 13. The head member 64 likewise has a conical milled bearing surface 66 which is adapted to engage the conical surface 63 to effect a metal to metal seal between chamber 62 and a chamber 67, Figs. 2 and 5, which is thus separated from chamber 12. An externally-threaded

nut member 68 screwed into the internal threads of chamber 13, engages an annular shoulder 69 of the head 64 and forces the same into metal to metal sealing engagement to completely seal off chamber 62 from chamber 67. The member 68 has a plurality of radially extended passages 70 which connect with longitudinal passages 71 and in that way connect chamber 62 with chamber 13, see Fig. 5.

The member 65 has sealed therein a cylindrical piece 72 of glass or other material having a substantially negligible coefficient of expansion. The sealing is effected by a cylinder of packing material 73 surrounding the glass cylinder 72. Through this glass cylinder 72 extends a bore 74 of minute cross-sectional area. The showing of this bore in Fig. 5 is very greatly exaggerated for the purpose of illustration, as it is very little more than a capillary opening constituting a limit port for determining and controlling the flow of gas from the tank 33 to the passages leading to the breathing line. The bore 74 terminates at its outer end in a chamber 75 and at its inner end in a chamber 76 which through a passageway 77 leads to chamber 67. A cap member 78 encloses the chamber 75 except for a screen 79 which covers the opening to the chamber 13.

A cap screw 80 is provided with a milled conical face 81 which is adapted to engage a correspondingly milled conical face 82. When the cap screw, which has a portion externally threaded, is screwed into the internal threads of chamber 13 so as to bring the milled conical surfaces 81 and 82 into firm contact, a metal to metal seal is provided which completely seals in chamber 13 from outside air.

The positioning of screens 58 in the center of tank chamber 35 has an important part in relation to the limit port 74, for this port is so small, a very tiny fragment of dust such as metal dust from the walls of chamber 35 could block the limit port and thus cut off delivery of gas, which might destroy an aviator using the device.

It will be seen from the above description that gas from chamber 35 flows through the port 61 into chamber 62, thence through openings 70 and 71 into the chamber 13. Thence the gas flows through the screen 79, the limit port 74, chamber 76, and passageway 77 into chamber 67. From chamber 67 the gas flows through a port 83, Fig. 2 into a chamber 84 beneath a valve block 85.

We prefer to make this valve block of silver so that there can be no possibility of leakage at this point. The valve block 85 is provided with a conical milled surface 86 which engages a correspondingly conical milled surface 87 surrounding the chamber 84 in valve block 10. A nut 83 is screwed into threaded walls 89 of a valve chamber 90 and engages an annular shoulder 91 on valve block 85 by which the sealing contact on conical contact surfaces 86 and 87 may be effectively established.

A port 92 leads through the center of valve block 85 to needle valve 93. A shank 94 of needle valve 93 extends through a guide 95 formed with openings 96, Figs. 2 and 4, which communicate through an annular opening 97 with the valve chamber 90.

The valve stem 94 has thereon a valve disc 98 on which is a valve ring 99 adapted to engage a knife-edged valve seat 100. A tubular piece 101 is secured to an externally threaded nipple 102 at the upper end of the main valve casting 10 by means of an internally-threaded nut 103, which has a ring 104 overlapping an annular

shoulder 105, Fig. 2. The members 98 and 99 are engaged by a strong spring 106 which surrounds a part 107 of valve stem 94 extending above the disc 98 and valve member 99.

5 The upper end of stem part 107 is adapted to slide freely in an opening 108 in the lower part of a plunger 109 which is in alignment with the opening in guide member 95. The valve stem is, therefore, free to slide in openings through guide member 95 and into the plunger head 109, actuated by the force of spring 110 surrounding the lower part of valve stem 94 and engaging the lower surface of disc member 98 and the upper part of guide member 95.

10 15 A cam lever 111, Figs. 1 and 2, has a cam head 112, a curved arm portion 113 and a straight arm portion 115. A cross bar 116 extending through cam member 111 at the end of the straight arm portion 115 thereof, adapts the bar readily to be 20 grasped by one hand and swung from its down position, as shown in Fig. 2, which is the valve closing position, to an up position, which is the valve opening position. The surface of cam head 112 engages a ball 116 in a pocket 117 in the top 25 of plunger member 109. In the down position of Fig. 2, the ball engages a notch 114 in cam head 112 which holds the parts against accidental displacement but still so that the handle can be swung very easily.

30 The cam arm is formed with a transverse slot 117' diametrically opposite from the notch 114. The slot 117' engages a pin 119 extending across between a pair of arms 120 and 121, Fig. 1, and the top of extension member 101. Thus the operating handle is not permanently affixed to the valve, but is held in valve-closing relation by engagement of the ball 116 in the notch 114. When the lever system is pulled up to valve-opening position the slot 117' drops off of pin 119 and 40 the lever is discarded, thus insuring that the lever cannot be operated accidentally to close the valve after once the valve has been opened.

45 In the position of the parts of Fig. 2 with the straight part 115 of handle 111 down, the needle valve sliding assembly has been brought to its maximum depressed position where the spring 106 is very considerably compressed, acting to hold the needle valve member 93 firmly in valve closing position over the opening 92 in the said 50 silver valve piece 85. When the handle 111 has been swung upwardly through an arc of something like 180°, the valve parts, including valve disc 98, will be moved upwardly a greater distance than the maximum expansion of strong 55 spring 106. This releases the lighter spring 110 to move the valve ring 99 into engagement with the knife-edged valve seat 100 with sufficient force to block any leakage of gas from chamber 90.

60 The oxygen gas is thus freed to flow through apertures 96 in guide member 95 and through annular chamber 97 to valve chamber 90. Flow of the gas or leakage from the system is prevented by the contact of valve ring 99 with knife-edged 65 valve seat 100. However, the oxygen flows from chamber 96 through a port 122 into a chamber 123 from which the gas goes through a horizontal port 124 to and through a nipple 125 which connects with tubing 126 going to a nipple 127 formed on a tubular extension 128 which leads to a mouth mask 129.

70 From the above arrangement it will be seen that at all times when the chamber 35 of gas container 33 is filled with gas at an adequate pressure, this gas has been passing through the

tiny limit port 74 and is present in the passageway 92 leading to the needle valve. The gas is then ready to be delivered in a continuous stream in a quantity measured by the limit port itself at the delivery pressures from chamber 35 any time the handle 111 is swung from its depressed position of Fig. 2 to its upright position. It is therefore only necessary for the aviator forced to bail out at high elevations to swing the mouth mask 129 into his mouth with one hand and to swing up on the lever assemblage 111 with the other hand and the necessary oxygen is thereupon being delivered to the breathing line going to the aviator.

The advantages of our invention have been given somewhat in detail in the foregoing description. A primary advantage resides in the complete separation of all passages and chambers for filling the high pressure containers with oxygen gas from the passages and chamber for delivering the oxygen gas from the container to the breathing line. It is necessary to have a gas container which can be readily filled, since the valve assembly must be united with the containing tank permanently and in sealing relation. Hence supplying oxygen to the container or obtaining a container filled with oxygen at the desired high pressure can not be accomplished by substitution of a filled container for an empty container as is true of supplies of therapeutic gases under most ordinary conditions of use. So the means in the valve assembly for filling or refilling the container 33 entirely independently of any passages for taking gas from the container 33 to the breathing line, is a highly advantageous and important feature for safeguarding against getting dust particles into the minute limit port orifice, which might stop flow of gas therethrough.

A further great advantage of our invention resides in the means in the valve assembly which prevents leakage or waste of gas either in supplying it to the aviator or while the high pressure container is being filled or refilled. Thus filling can only take place after connection to the large tank supply has been sealed into the filling opening, and the filling passages are sealed by valve action immediately after the large supply has been turned off. Valve means seal in the filling passageway and the tank itself to prevent escape of gas after filling. And when the valve controlling handle for opening flow of gas to the breathing line is swung into a position to open the valve thereto, there is simultaneously applied to a valve seat in the flow chamber a valve closure which definitely prevents any leakage.

A further great advantage of our invention resides in simplifications which have greatly reduced both the length and the bulk of the valve assembly. A particular feature which aids in this, resides in the use of an elongated limit port mounted in transverse relation to the axial center of the whole valve assemblage, so that at the same time a desired length of the minutely small limit port is obtained and yet the length of the valve assemblage is but little increased.

A further advantage of our invention resides in the effective means for quick opening of the valve which delivers the gas to the aviator. The valve handle 111 in its depressed position extending parallel with the valve assemblage securely locks the parts in position to prevent any flow of oxygen. At the same time, because of the cam head engaging the ball roller, it is very easy to swing the valve handle into its upright posi-

tion which brings about simultaneous opening of the gas delivery valve and closing of the shut off valve from the chamber. The swinging of the valve handle from closed to open position is so easy that it can readily be done with one or two fingers of a single hand and never requires holding the valve assemblage with the other hand, as is true of a number of rotary valve devices.

A very great advantage of our invention is found in the screening means for gas going through the limit port to the breathing line, which screening means is located adjacent the center of the gas container away from the inner walls thereof, which is a source of metal flakes and dust. The advantage of this arrangement is that it very effectively assures that no flakes or particles of dust shall go to the limit port, which is so small in cross-section that a very tiny flake or dust fragment might cause a stoppage of flow through the limit port with disastrous results to the aviator.

A further great advantage of our invention comes from the provision of spring means for opening the valve for delivery to the aviator in association with a handle member non-permanently attached to the valve assembly, which in its down position is effectively held against accidental misplacement, thus definitely sealing the oxygen gas within the container, and which when it is operated to permit a spring to open the valve, becomes disconnected from the assemblage when it will be discarded and there will be no chance in the descent of the aviator for an accidental closure of the valve, which might happen from the contact with the parachute cords or from other reasons, and which also would be disastrous.

We claim:

1. In a valve assembly and container of oxygen 40 under pressure, permanently connected and sealed one to the other, a delivery tube located toward the axial center of the container and extending a considerable distance down into said chamber, a set of screens at the open end of said tube, a 45 set of passages through the valve assembly for conveying oxygen gas from the container to a breathing line, said passages including a limit port of minute cross-sectional area and also including a valve chamber in said passages located 50 on the other side of the limit port from the delivery tube, the location of the delivery tube and of the screen system thereon operating to prevent any scale or dust from being moved to the limit port which otherwise might be blocked 55 by very small fragments of tank scale or dust.

2. In a valve assembly and container of oxygen gas permanently connected and sealed one to the other, a set of passages through the assembly for conveying oxygen gas from the container to a breathing line, a valve in said passages and spring means tending to hold the valve in open position, a handle non-permanently attached to the top of the valve assembly having a cam head adapted to hold the valve closed when the handle 65 is down, said handle being connected to the valve assembly in such manner that when it is thrown into an upright position the spring will actuate the valve into open position and the handle will become disconnected from the assembly so that 70 the valve can not be accidentally closed.

3. In a valve assembly and container of oxygen gas permanently connected and sealed one to the other, a set of passages through the assembly for conveying oxygen gas from the container to a breathing line, a valve in said passages and spring

means tending to hold the valve in open position, a handle non-permanently attached to the top of the valve casing embodying a cam head a curved portion and a straight portion, the latter adapted to lie substantially parallel with the valve assembly when the handle is down in valve closing position, a standard at the end of the assembly embodying a transverse pin, a transverse slot in the cam head of the handle adapted to be hooked over the pin, whereby when the handle is thrown into its upright position to permit the spring to open the valve the handle will become disconnected and drop away from the assembly so that the valve can not be accidentally closed.
